(57) **CLAIM**

The ornamental design for a beverage container, as shown and described.

DESCRIPTION

FIG. 1 is a front, top perspective view of the beverage container of the present invention;

FIG. 2 is a rear, bottom perspective view of the beverage container of the present invention;

FIG. 3 is a top plan view of the beverage container of the present invention;

FIG. 4 is a side elevation view of the beverage container of the present invention, both sides being identical;

FIG. 5 is a front, elevation view of the beverage container of the present invention, which is identical to a rear elevation view; and,

FIG. 6 is a bottom plan view of the beverage container of the present invention.

The broken lines showing of the cap and bottom features in all figures are for illustrative purposes only and form no part of the claimed design.
